UNITED STATES PATENT OFFICE.

JAMES P. CONROY, OF NEW YORK, N. Y., AND ARTHUR L. ZWISLER, OF KALAMAZOO, MICHIGAN.

DESIGN FOR A HEATER.

Application filed June 12, 1924. Serial No. 9,860. Term of patent 14 years.

To all whom it may concern:

Be it known that we, JAMES P. CONROY, a citizen of the United States, residing at New York, in the county of New York and State of New York, and ARTHUR L. ZWISLER, a citizen of the United States, residing at Kalamazoo, in the county of Kalamazoo and State of Michigan, have invented a new, original, and ornamental Design for a Heater, of which the following is a specification, reference being had to the accompanying drawing, forming part thereof.

The figure is a perspective view of a heater, showing our new design.

We claim:

The ornamental design for a heater, as shown.

JAMES P. CONROY.
ARTHUR L. ZWISLER.
